UNITED STATES PATENT OFFICE.

CHARLES H. OSLUND, OF WORCESTER, MASSACHUSETTS, ASSIGNOR TO THE O & J MACHINE COMPANY, OF WORCESTER, MASSACHUSETTS, A CORPORATION OF MASSACHUSETTS.

WIPING-DOWN DEVICE.

Application filed July 7, 1920. Serial No. 394,467.

To all whom it may concern:

Be it known that I, CHARLES H. OSLUND, a citizen of the United States, residing at Worcester, in the county of Worcester and 5 State of Massachusetts, have invented a new and useful Wiping-Down Device, of which the following is a specification.

This invention relates to a device for wiping down the two over-lapping ends of a 10 label which passes entirely around the article to be labeled, although it is capable of wiping down the edge of a label even when it does not over-lap.

The principal object of the invention is to 15 provide for automatically wiping along the edge of the label for the purpose herein specified after the label has been placed in position by the ordinary wiping operations heretofore employed, or by any of them. 20 It is also an object of the invention to provide this feature in convenient and simple form adapted for use with a well known type of wiping machine without adding any unnecessary complications to it or providing 25 any additional supporting and guiding devices.

Further features and advantages of the invention will appear below.

Reference is to be had to the accompanying drawings, in which—

Fig. 1 is a side view of a part of a rotary labeling machine having an attachment constructed in accordance with this invention and shown in its normal inactive position;

Fig. 2 is a sectional view taken radially on the line 2—2 of Fig. 1, showing the operative connections;

Fig. 3 is a side view similar to Fig. 1, on enlarged scale, showing parts in section 40 and illustrating the elements in the wiping position;

Fig. 4 is a sectional view on the line 4—4 of Fig. 3;

Fig. 5 is a view of the sliding bushing for 45 controlling the position of the wiper;

Fig. 6 is a plan of the cam used in this particular machine;

Fig. 7 is a plan showing the bottle in section and illustrating how it goes through 50 a pair of wipers to wipe the label around the bottle neck;

Fig. 8 is a similar view showing the bottle neck farther along, after the label has been wiped down upon it, and

Fig. 9 is a side view of the bottle on en-

larged scale, showing in dotted lines one position of the wiping operation and showing the completion of it in full lines.

When a bottle or other article to be labeled is applied to a rotary table 10 and passed through a pair of wipers 11, the label L can be wiped entirely around it either by the simple wipers shown or the use of additional wiping devices of a similar character, so that the two ends over-lap at 12 in Fig. 8.

Several devices have been invented for the purpose of more smoothly and completely over-lapping the ends of a label in a case like this but so far as we are aware, they 70 usually work on the principle of the wipers 11 or, in addition thereto, the employment of one or more wipers operating transversely with respect to the length of the bottle.

The mere wiping of the label down by the two wipers 11 is not sufficient under some circumstances as the over-lapping ends can not sometimes be brought into such a smooth condition as is desirable, especially 80 on the conical or ovate surface of a bottle neck.

This invention is designed to provide for positively smoothing out this over-lapping end after it is brought into substantially its 85 final position. In other words, this is a finishing operation consisting in the wiping and smoothing down of the over-lapping end of the label.

The invention is shown as applied to a 90 labeling machine which involves a rotary table 10, turning about a center, but it can be applied to labeling machines in which the bottle B to be labeled is moved rectilinearly or in any other way.

However, on this type of machine there is a vertical rod 13 operated by mechanism below, not shown herein as it is illustrated in several prior patents. It extends up through a stationary sleeve 14 mounted on the table and has a clamp 15 at its top adapted to clamp down on the top of the bottle B and hold it in position against a stop 16 while the bottle passes around on the table through a part of a complete revolution. I have made use of these features to support and guide the parts which constitute the present improvement.

Mounted below the rotary table, I have placed a cam 18 in stationary position and

on the table I have placed a bracket 19 having a pivot pin 20 thereon for supporting a lever 21. A spring 22 holds the operative bifurcated end of this lever down. The other 5 arm of the lever supports a roll 24 which enters the cam as the table rotates and is controlled by the side walls of the cam during the rotation of the table.

When the cam is engaged by the roll 24, 10 its inner wall forces this roll out against the action of the spring 22 and the bifurcated end 23 moves upwardly a pin 25 which projects into the notch between the bifurcations. This pin is mounted on a rod 26 15 which passes freely up through a perforation in the table and has secured to it at the top a plate 27. This plate is provided with a cylinder 28 which moves positively with the rod 26 and is guided on the sleeve 20 14 fixed to the table. Within its upper end, this cylinder 28 carries a sliding bushing 30 which is of a general cylindrical form slidably engaging the rod 13 and has a flange 31 at the top adapted, when in the position 25 shown in Fig. 3 for example, that is when it is raised from its normal low position, to rest on the top of the sliding cylinder 28 where it has no active function.

However, when the cylinder 28 is in its 30 lowermost position, as shown in Fig. 1, the lower end of the bushing 30 comes into contact with the top of the stationary cylinder 14 and this occurs previously to the movement of the cylinder 28 to the lowest position. The result is that this sliding bushing 35 can move down no further and as the sleeve 28 continues to move down to the lowermost position shown in Fig. 1, the top flange 31 of the sliding bushing then acts as a stationary 40 member and the end of a lever 33 comes into contact with it as shown in Fig. 1. This lever 33 is pivoted on a pair of projections 34 mounted on a bracket 35 positively fixed to the cylinder 28. Therefore, when it comes 45 down into the position shown in Fig. 1, the outer end of the lever 33 is depressed. This, by means of a link 36, depresses an arm 37 fixed on a shaft 38 supported by the bracket 35. On this shaft 38 is an arm 39 normally 50 pulled upwardly by a spring 40 and also an arm 41 carrying a soft felt or leather wiping roller 42. Therefore, the movement of the parts downwardly from the limiting position shown in Fig. 1 raises the wiping roller 55 into inoperative position as illustrated in that figure.

Now, however, as the table rotates and the label L is applied around the bottle into the 60 position shown in Fig. 8, the roll 24 engages the cam surface and is forced outwardly, moving the rod 26 and cylinder 28 upwardly as shown by the arrow in Fig. 3. The top of the cylinder soon picks up the bushing 30 and by that time it has lifted 65 the bracket 35 far enough so that the arm

33 is now perfectly free from the top of the bushing. This brings the parts into the position shown in full lines in Figs. 3 and 9. As the table continues to rotate and the eccentricity of the cam to increase, the 70 bracket 35 is lifted and the roller 42 goes to its uppermost position shown in Fig. 9 in dotted lines.

All this time the roller 42 has been rolling 75 along the vertical seam formed by the overlapping end of the label. The cam is so shaped that the roll then goes down this line and performs its finishing operation on the downward stroke at the end of which the roll is drawn back into the position shown 80 in Fig. 1 in the manner above described.

It will be seen that although the operation 85 is performed by a cam and the cylinder 28 is raised positively and lowered by spring action, the roller 42 is pressed against the label by spring pressure due to the spring 40 and thus a gentle yielding action is secured. This constitutes a safe and positive means for effectually smoothing out a label previously wound around an article, particularly 90 the neck of a bottle without adding much mechanism to the labeling machine, particularly if applied to the type of machine illustrated.

Although I have illustrated and described 95 only one form of the invention and illustrated it as applied to a single type of labeling machine, I am aware of the fact that it can be formed with many modifications and applied to numerous types of labeling machines without departing from the scope of the invention as expressed in the claims. Therefore I do not wish to be limited in these respects, but what I do claim is:—

1. In a labeling machine, the combination 100 with means for wiping a label all the way around an article and over-lapping it, of a roller and means for moving the roller longitudinally along the over-lapping end of the label.

2. In a labeling machine, the combination 105 with means for wiping a label on an article, and lapping one end over the other, of a label pressing device, and means for moving said pressing device up and down along the over-lapping end from one edge 110 of the label to the other.

3. In a labeling machine, the combination 115 with means for wiping a label around an article and over-lapping its edge, of a support movable longitudinally with respect to the axis of the article to be labeled, and means carried by said support for effecting a pressing and rolling action progressively in a straight line from one edge of the label 120 to the other and along said overlapping part to smooth out the edge of the label and complete the wiping operation.

4. In a rotary labeling machine, the combination of a rotary table, a rod carried 125

thereby having means for clamping the article to be labeled down on the table, means for applying the two ends of the label around the article and lapping one over the other, and means guided by said rod for wiping down the overlapping edge of the label.

5. In a rotary labeling machine, the combination of a rotary table, a rod carried thereby having means for clamping the article to be labeled down on the table, means for applying the two ends of a label around the article and lapping one over the other, a stationary cam under the table, a lever 10 adapted to engage the cam and be operated thereby, and means guided by said rod for wiping down the over-lapping edge of the label, said lever having connections 15 controlling the vertical position of said 20 means.

6. In a labeling machine, the combination with a support for the article to be labeled and a clamping rod movable therewith and parallel with the axis of the article, 25 of a sleeve carried by the table in which the clamping rod is adapted to move up and down, a cylinder slidably mounted on said sleeve, means below the table for operating said cylinder, and means carried by the 30 cylinder for performing a finishing wiping operation on the label applied to said article.

7. In a labeling machine, the combination with a support for the article to be labeled and a clamping rod movable therewith, of a 35 sleeve carried by the table in which the clamping rod is adapted to move up and down, a cylinder slidably mounted on said

sleeve, means below the table for operating said cylinder, a bushing slidably mounted on top of said cylinder adapted to rest on the top of said sleeve when the cylinder is in its lowermost position, a bracket carried by said cylinder, a lever supported by the bracket and positioned for its end to engage the top of said bushing when the sleeve is lowered and to be freed therefrom by the raising of the cylinder, and a roller wiper supported by said bracket and controlled by said lever.

8. In a wiping device, the combination 50 with a vertical guiding rod, a sleeve surrounding it, a bushing mounted to slide on said rod above the top of said sleeve, a member slidable up and down the sleeve along the outside and adapted to move the bushing up and down, a bracket on said member, a lever carried by said member and having one end in position to be controlled by the position of said bushing, a pivoted arm having a rolling wiper thereon, means carried by said bracket for applying a spring pressure to said arm to force the roller toward the article to be labeled and means carried by said bracket and operated by said lever for positively 55 moving the roller back out of operative position when the said member is moved to one extreme position, whereby the roller will operate along a label during a part of the motion of said member and will then 60 be retracted therefrom.

In testimony whereof I have hereunto affixed my signature.

CHARLES H. OSLUND.
